UNITED STATES PATENT OFFICE.

WILHELM POHL, OF DITTERSBACH-GRUESSAU, GERMANY, ASSIGNOR TO GUSTAVE WERNER, OF PHILADELPHIA, PENNSYLVANIA.

GRATE MECHANISM AND CLEARING MEANS THEREFOR.

1,041,344.

Specification of Letters Patent.

Patented Oct. 15, 1912.

Application filed February 5, 1912. Serial No. 675,857.

To all whom it may concern:

Be it known that I, WILHELM POHL, a subject of the Emperor of Germany, residing at Dittersbach-Gruesau, Germany, have 5 invented a new and useful Grate Mechanism and Clearing Means Therefor, of which the following is a specification.

My present invention consists of a novel construction of a grate mechanism and novel 10 means for clearing the grate from any ash, clinkers or foreign material which has lodged therein and thus preventing the proper combustion of the fuel.

My invention further consists of a novel 15 construction of a grate mechanism, a novel manner of mounting the same and novel means for affecting the dumping of the grate.

My invention further consists of a novel 20 construction of ash clearing mechanism which is mounted in such a manner with respect to the grate proper that it may be readily reciprocated so that any clinkers or ash remaining between the grate bar members 25 will be positively loosened and broken up in such a manner that they will fall into the ash pit of the furnace.

It further consists of other novel features 30 of construction, all as will be hereinafter fully set forth.

For the purpose of illustrating my invention, I have shown in the accompanying drawing one form thereof which is at present preferred by me, since the same has been 35 found in practice to give satisfactory and reliable results, although it is to be understood that the various instrumentalities of which my invention consists can be variously arranged and organized and that my invention 40 is not limited to the precise arrangement and organization of these instrumentalities as herein shown and described.

Figure 1 represents a plan view of a grate and clearing mechanism therefor embodying my invention. Fig. 2 represents a side elevation thereof. Fig. 3 represents a sectional elevation of Fig. 1 showing more clearly details of construction.

Similar numerals of reference indicate 50 corresponding parts in the figures.

Referring to the drawings, my novel grate construction and clearing mechanism therefor is adapted to be employed with any desired or conventional type of furnace or in

all cases where a bed of fuel is supported 55 upon a grate mechanism.

1 designates a supporting frame of any desired or conventional construction in which is pivotally mounted on opposite sides of the frame at 2, trunnions 3 which in 60 the present instance are integral with the grate proper 4. The members 3 are provided with laterally extending shoulders 5 forming bearings or guides and the under-face of each of these trunnions or support- 65 ing members 3 is beveled, as seen at 6.

7 designates grate clearing members which are provided with upwardly extending teeth or prongs 8, having any desired contour and adapted to extend between the bars of the 70 grate 4. In the present instance, I employ two of the grate clearing members 7, the same being connected on each side by a rod or bar 9 whereby they will be moved in unison, it being best understood by reference to 75 Figs. 1 and 2, that one of these bars is located approximately centrally of the grate, while the other grate clearing member is located near one end of the grate, whereby the grate clearing members 7 will coöperate with 80 the grate for substantially its entire length. The grate clearing members 7 are slidably mounted on the supports 3, it being seen that the upper portions of the members 7 are provided with laterally extending flanges 85 10, which seat on the shoulders 5, and are guided thereby, and the members 7 are recessed in order to conform to the contour of the lower end of the supporting members 3.

11 designates one or more arms one end of 90 each of which is pivoted at 12 to one of the clearing members 7 while the other end thereof is mounted on a shaft 13 suitably journaled in the frame 14 of the furnace construction.

15 designates an arm mounted on the shaft 13 and provided with an actuating handle or lever 16 which may extend to any desired point convenient to the operator.

In the operation, when it is desired to 100 clear the grate 4 of any ash, clinkers or foreign material, which is clogging the space between the grate bars, the lever 16 is actuated thereby rocking the arms 11 and causing the grate clearing members 7 to 105 move forwardly and rearwardly, the result of which is that any ash, foreign material or clinkers retained between the grate bar

members will be broken up so that the same will fall into the ash pit of the furnace.

Special attention is directed to the fact that the grate 4 is pivotally supported at 5 2, the pivotal point being on one side of the center of the grate whereby when the handle 16 is actuated to bring the grate clearing members 7 into the position seen in dotted lines, the grate will rock on its fulcrum 2 10 into the position seen in dotted lines in Fig. 2, so that the same may be readily dumped with a minimum amount of labor.

Attention is further directed to the fact that in my novel construction the grate may 15 be cleared of ashes and also dumped by the same lever or handle.

In accordance with my present invention, I have devised a novel and simplified construction of a grate mechanism and clearing means therefor which is of simple and compact construction and which may be 20 economically built, the parts being constructed and arranged in such a manner that the clearing members are not liable to 25 become distorted or destroyed due to the heat from the bed of fuel, and my device may be economically manufactured in practice. The grate members and the teeth of the grate clearing members 7 may have 30 any desired contour and in order to show one construction which will give advantageous results in practice, I have shown the grate members 4 as converging from their top to their bottom and the teeth 8 of the 35 grate clearing members 7 as converging upwardly from their bottom to their top.

It will now be apparent that I have devised a novel and useful construction of a grate mechanism and clearing means therefor, which embodies the features of advantage enumerated as desirable in the statement of the invention and the above description, and while I have, in the present instance, shown and described a preferred 45 embodiment thereof which has been found in practice to give satisfactory and reliable

results, it is to be understood that the same is susceptible of modification in various particulars without departing for the spirit or scope of the invention or sacrificing any 50 of its advantages.

Having thus described my invention, what I claim as new and desire to secure by Letters Patent, is:—

1. The combination of a support, trunnions pivotally mounted therein and having laterally extending shoulders, a grate carried by said trunnions, a plurality of grate clearing members adapted to slide on said shoulders and provided with teeth projecting between the bars of the grate, a rock shaft, arms connecting said rock shaft and one of said grate clearing members, means for connecting said grate clearing members, an arm carried by said rock shaft, and a lever secured to said arm, the pivotal point of said trunnions being on one side of the center of the grate, whereby when said lever is brought to one of the extreme positions said trunnions will turn on their fulcrum 70 to dump the grate.

2. The combination of a support, members pivotally mounted therein, a grate carried by said members and having on opposite sides laterally extending shoulders, 75 a grate clearing member adapted to slide on said shoulders and provided with teeth projecting between the bars of the grate, a rock shaft operatively connected with said grate clearing member, and an actuating 80 lever operatively connected with said rock shaft, the pivotal point of said first members being on one side of the center of the grate whereby when said actuating lever is brought to one of its extreme positions said 85 first members will turn on their pivots to dump the grate.

WILHELM POHL.
